(57) **CLAIM**

The ornamental design for an ultrasonic level meter as shown and described.

DESCRIPTION

FIG. 1 is a front elevational view of an ultrasonic level meter;

FIG. 2 is a left side view thereof;

FIG. 3 is a top plan view thereof;

FIG. 4 is a left side perspective view thereof; and,

FIG. 5 is a right perspective view thereof.

The broken lines shown in the figures are for the purpose of illustrating portions of the ultrasonic level meter that form no part of the claimed design.

1 Claim, 5 Drawing Sheets
